UNITED STATES PATENT OFFICE.

FRANK W. MIX AND GEORGE B. COWLES, OF NEW BRITAIN, CONNECTICUT,
ASSIGNORS TO THE CORBIN CABINET LOCK COMPANY, OF SAME PLACE.

TRUNK-LOCK.

SPECIFICATION forming part of Letters Patent No. 331,427, dated December 1, 1885.

Application filed March 30, 1885. Serial No. 160,596. (Model.)

To all whom it may concern:

Be it known that we, FRANK W. MIX and GEORGE B. COWLES, citizens of the United States, residing at New Britain, in the county 5 of Hartford and State of Connecticut, have invented certain new and useful Improvements in Trunk-Locks, of which the following is a specification.

Our invention relates to improvements in 10 that class of trunk-locks in which the lock proper is mainly inclosed within a round boss on the end of the hasp.

The operation of our lock is substantially 15 the same as in prior locks of the same class.

15 The object of our improvements is to so simplify the construction as to save milling and other labor, whereby the lock can be produced at less cost than heretofore.

In the accompanying drawings, Figure 1 20 is a front elevation of our lock with the cap-plate removed. Fig. 2 is a transverse section of the same on line *xx* of Fig. 1, together with the keeper. Fig. 3 is a section of the circular bolt. Fig. 4 is a side elevation of the 25 central post. Fig. 5 is a sectional view of the circular bolt, illustrating another way of securing the central part therein. Fig. 6 is a side elevation of the key for our lock, and Fig. 7 is a view of the rear side of the bolt.

30 A designates the swinging member of the hasp, in the lower end of which is formed the lock proper, the same being mainly within the recessed boss or circular projection B, Fig. 2. On the back of the boss B is a smaller 35 central boss, *a*, Fig. 2, the thickness of which is fully equal to or a little in excess of that of the metal in the back of the keeper-socket D, Fig. 2.

C designates the circular bolt, having a central hub, *b*, by which it is centered in its partial revolution within the case. For a double-bitted key like Fig. 6, two curved slots, *c*, are made through the body or disk portion of the bolt C, said slots being made at a point farther from the axis of said bolt than the periphery of the central hub, *b*, so that they may be made by punching on a power-press, and thereby avoid milling. These slots are for the points *d* of the key to enter for throwing the bolt. For a single-bitted key only one of the slots *c* will be required. The bolt C is also provided with a fence, *e*, Fig. 1, for

the tumblers *f* to act upon. The central post, *g*, is formed of wire and then secured within the bolt. Fig. 3 shows the bolt drilled and countersunk ready to receive said post, in which it will be noticed that the countersink is quite deep. The end of the post *g* is headed and the head is beveled on both sides, as shown. In order to secure it within the bolt, it is driven in until the under side of its head rests upon the bottom of the countersink in the bolt, and then the metal in the central hub, *b*, which surrounds said head, is riveted down upon the opposite side of the head of the post *g*, to prevent it from working endwise out of place.

As in prior locks of this class, the part of the bolt which engages the keeper D is an oblong button, E, Figs. 2 and 7. We make this 70 button E of sheet metal by merely cutting it out with dies and beveling or countersinking its square central hole. It is then secured to the bolt by riveting it upon the squared tenon at the end of the central hub, *b*. The 75 riveting of the button E and central post, *g*, can be done at one operation.

If desired, instead of the central post with a double-beveled head, as in Fig. 4, a post, *g'*, may be made with a raised shoulder, *h*, near 80 the middle of its length, and the hole in the bolt C be countersunk at both ends, and then secure the post by riveting down its end, all as shown in Fig. 5.

We claim as our invention—

1. In a lock of the class shown and described, the circular bolt having central hub and disk-shaped portion, with the curved slot *c* made through said disk-shaped portion, substantially as described, and for the purpose 90 specified.

2. In a lock of the class described, the circular bolt having the central hub and hole with deep countersink formed in said hub, and the central post, *g*, having the double-beveled head secured within said countersunk hole in the hub, substantially as described, and for the purpose specified.

FRANK W. MIX.
GEORGE B. COWLES.
